VARIABLE DISCHARGE MECHANISM

Thomas R. Ellerbeck, Salt Lake City, Utah

Application April 12, 1946, Serial No. 661,535

17 Claims. (Cl. 222—135)

1

This invention relates to variable discharge mechanism.

The instant application constitutes a continuation-in-part of my copending allowed application Ser. No. 408,225, filed August 25, 1941, entitled "Feed and Discharge Controls," the same having been allowed October 26, 1945, and thereafter abandoned in favor of the present application. The instant application is also a continuation in part of my copending application Ser. No. 438,047, filed April 7, 1942, entitled "Methods of Calcining and Calcining Apparatus," now Patent No. 2,451,024, dated October 12, 1948.

Embodiments of the novel variable discharge mechanism may be used for regulating the discharge from a variety of types of material-treatment or processing chambers, especially those where very close control over discharge is necessary or desirable. An outstanding example is the calcining apparatus of my above-mentioned copending application Ser. No. 438,047.

In some instances, use of the novel variable discharge mechanism will be found advantageous for the purpose of feeding material in controlled amounts from a supply thereof, according to a preconceived pattern.

Among the objects of the invention are the following:

First: To provide discharge mechanism which is capable of varying the rate of discharge of material at various locations along a single discharge opening relative to other locations along the same opening.

Second: To provide discharge mechanism which is capable of varying, thusly, the rate of discharge of material through a plurality of openings relatively to one another.

Third: To provide mechanism that will control, thusly, the flow through a plurality of discharge openings, by means of a single drive arrangement.

Fourth: To provide discharge mechanism, as set forth above, wherein the drive is variable speed means which will readily change the speed of travel of the discharge mechanism, and, consequently, the total rate of discharge of material without changing the proportional flow through each opening or through various sections of each opening.

Fifth: To provide mechanism that is comparatively economical to operate and to maintain in good running condition, and in which necessary adjustments can be easily made without shut downs.

Sixth: To provide mechanism that is relatively inexpensive to construct.

2

A very useful and preferred type of apparatus pursuant to the invention includes a plurality of elongated feed spouts forming a series of gravity discharge openings, the elongated axes of the discharge openings being substantially parallel to each other. Discharge mechanism is mounted below the series of discharge openings, and is arranged to be driven by a single variable speed drive. The discharge mechanism is adjustable, so that the discharge from and flow through the several openings in the series may be varied differentially relative to one another, and so that the flow from any discharge opening of the series may be varied differentially along the length of that discharge opening.

These and other objects and features of the invention will be more fully understood from the following detailed description of the several specific embodiments illustrated in the accompanying drawings, in which:

Fig. 1 represents a longitudinal vertical section taken centrally through a calcining apparatus of my above-mentioned application Ser. No. 438,047, one preferred form of discharge mechanism pursuant to the present invention being employed therewith;

Fig. 2, an enlarged detail view of that portion of Fig. 1 enclosed by the dotted line 2, illustrating actual discharge of material;

Fig. 3, an end elevation of the pile of discharged material shown in the extreme lower part of Fig. 1;

Fig. 4, a fragmentary vertical section taken on the line 4—4 of Fig. 1;

Fig. 5, a view in perspective looking down upon the discharge mechanism per se, illustrating certain of the more prominent parts thereof;

Fig. 6, a fragmentary top plan view of the extreme left-hand portion of the apparatus of Fig. 1, showing a preferred arrangement of drive means for the variable discharge mechanism;

Fig. 7, a diagram indicating some of the possible movements of a displacement bar of the discharge mechanism;

Figs. 8 through 8D, detail perspective views, illustrating, respectively, various ways in which the profile of a displacement bar might be configurated for achieving various desired additive differential discharge effects along any one discharge opening;

Fig. 9, a view similar to that of Fig. 2, but illustrating the use of a differently configurated displacement bar;

Fig. 10, a fragmentary detail view, somewhat enlarged, of a different type of selectively settable control means for the displacement bars;

Fig. 11, a diagram of the major portion of Fig. 1, drawn to a reduced scale, and showing in the barest outline the interior of the kiln divided into a series of approximate columnar spaces a' to f' , between which the flow of material through the kiln may be considered as divided;

Fig. 12, a chart which aids in the description of the principle of the variable or differential discharge characteristic of the invention;

Fig. 13, a view corresponding to that of Fig. 4 but illustrating discharge mechanism of alternate construction, wherein the stop plate, rather than the displacement member, is arranged to be moved;

Fig. 14, a vertical section taken on the line 14—14, Fig. 13;

Fig. 15, a plan of the movable stop plane above;

Fig. 16, a view substantially corresponding to that of Fig. 5, but illustrating another construction of variable discharge mechanism pursuant to the invention;

Fig. 17, a fragmentary side elevation, partly in section, of the inventive embodiment of Fig. 16 drawn to an enlarged scale; and

Fig. 18, a view in perspective of a fragmentary detail of Fig. 16.

Referring to the drawings: the calcining apparatus of Fig. 1, which is here only sketchily described because it is merely incidental to the invention proper, is equipped with the variable discharge mechanism of Figs. 4, 5 and 6, and includes a calcining chamber or zone 110, defined laterally by refractory side walls, as at 112, and refractory end walls 113 and 114.

Crushed material 55, such as limestone, descends from storage bins 55 to a feed hopper 150 under the influence of gravity, where it passes through a plurality of chutes 115 into the calcining chamber 110 in accordance with the controlled discharge of the calcined material 151 effected by operation of the variable discharge mechanism of the invention. For convenience, only a portion of the crushed material 55 and calcined material 151 are here illustrated, it being understood that such material extends throughout the complete breadth of the bin hopper and calcining chamber.

By means of respective sliding sleeves 116, the chutes 115 may be shortened or lengthened to vary the effective height of material within the calcining chamber 110. Rotation of hand-wheel 120, and, therewith, of the shaft 117, accomplishes this by raising or lowering the sleeves relative to their respective chutes, through suitable rock and pinion mechanism.

The calcination is accomplished within the calcining chamber 110 by means of gases that are conditioned to the proper temperature in a combustion or tempering chamber, which is advantageously disposed laterally of the calcining chamber against the refractory side wall 112 thereof, and preferably extends substantially co-extensive therewith in its longitudinal dimension.

The tempered gases are drawn, preferably by an induced draft, into direct contact with the material in the calcining chamber, through ports which extend through the refractory wall 112 separating the two chambers. These ports are preferably arranged in tiers, and are in registry with corresponding blind tunnels or passages 222, 223 and 224, respectively, that extend completely across the calcining chamber and terminate in respective transparently-closed observation ports disposed in the opposite refractory side wall.

In their extension across the calcining chamber,

the tunnels or passages are at least partially defined by respective tunnel elements 125, and at least partially by the intersticed floor surfaces 225 formed by the material to be calcined in assuming its natural angle of repose under the tunnel elements. The tempered gases of combustion flowing through the tunnels filter into and through the material to be calcined by way of the intersticed floor-defining surfaces 225.

The several refractory walls defining the calcining chamber 110 are preferably mounted on a structural steel frame 30 which in turn is supported on columns 30a.

Depending from the frame 30 and disposed directly below the calcining chamber 110 is a series of elongate spouts 31, each of which discharges finished product squarely onto a corresponding elongate stop plate 64 of the variable discharge mechanism, the rate of discharge through each individual spout being variably or differentially regulated.

The raw material 55, in its progress downward through feed chutes 115 and adjustable sleeves 116, enters the calcining chamber 110, and, by means of the uppermost tier of tunnel elements 125, is split up into approximately the transitory columns a' to f' , Fig. 11, closing around the tunnel elements in the successive tiers, thereby forming the tunnels 222, 223 and 224 already mentioned. This exposes the descending material to thorough permeation by the tempered gases drawn in from the combustion chamber. Thus, the calcining of the material proceeds until the lower portion of the chamber 110 is reached. Here, atmospheric air, which is drawn in through the discharge spouts 31, serves to cool the fully calcined material immediately prior to its discharge.

Refractory partitions 58 rest on the supporting framework 30 between adjacent discharge spouts 31, and define, at least partially, chutes 94 leading directly into the discharge spouts. From the latter, the finished product is deposited on the stationary stop plates 64, where it is arrested until removed by operation of variable discharge mechanism.

The novel variable discharge mechanism constituting the present invention may be embodied in various forms, the embodiment of Figs. 1 through 7 comprising a reciprocable frame 60, consisting of slotted longitudinal members 60a and of end members 60b and 60c, mounted, for example, on rollers 61 held rotatively in brackets 62 attached to a stationary framework. The stationary framework advantageously includes slotted longitudinal members 67 and stringers 63, Fig. 4, all rigidly connected to columns 30b. The stop or arresting plates 64 extend transversely of the reciprocating frame 60 to suit the spacing of the spouts 31, and are supported by the stringers 63. The lower portions of the stationary longitudinal members 67 form stationary supports, as will be apparent hereinafter.

The finished product in the spouts 31 rests on the plates 64 ready to be removed therefrom in relatively small quantities, which are varied, when necessary, in accordance with the progress of the calcining process taking place in the columns above the respective plates.

The finished product is advantageously removed by means of elongate displacement bars 65 extending lengthwise of the plates 64 and disposed intermediate the side edges thereof. The bottom face of each displacement bar clears the surface of the stop plate with which it is asso-

ciated, and the bar is subject to reciprocatory motion laterally of the plate.

In accordance with the invention, the unit reciprocatory strokes of the bars are subject to differentiation in agreement with the variation in product-removal requirements. For this purpose, the opposite end portions of each displacement bar, which extend first through the slots in the stationary members 67 and then through the slotted members 60a of the reciprocatory frame 60, Figs. 4 and 5, finally extend through and beyond openings 68a defined by jaws 68b of control dogs 68. The openings 68a are approximately V-shaped, but inverted, and the dogs 68 are secured to the frame 60, preferably adjustably, by means of bolts or screws 70 extending through slots 69 in the jaws 68b.

It should be noted that the displacement bars 65 rest upon and are supported by the lower slide-way portions of the longitudinal stationary frame members 67, but desirably do not contact the longitudinal reciprocatory frame members 60a in any way. Thus, the displacement bars are not influenced by the movement of frame 60 except when they are contacted by the dogs 68.

Reciprocation of the frame 60 on its supporting rollers 61 actuates all or part of the displacement bars, similarly or differentially, depending upon the settings of the respective dogs. The opening 68a in each dog is just wide enough at its apex to accommodate an end of a displacement bar 65, but diverges so as to afford an increasing amount of play for the end of the displacement bar accordingly as the dog is positioned upwardly therefrom. In reciprocating the frame 60, the respective displacement bars 65 push or spill more or less of the finished product from the plates 64, thus causing a gradual descent of the material in process, through the calcining chamber 110, see Figs. 1 and 2.

The representation in Fig. 2 is typical of all the spouts 31 and stop plates 64. Here, the displacement bar 65 is shown completely buried in the product 151a at the bottom of the superimposed column 'e', see Fig. 11. Supposing the bar 65 to have been moved towards the right from an initial position such as the dotted one at 65a to the full-line position at the right, it will then have pushed or spilled off the plate a certain quantity of the product 151a, of which a portion 151b is shown in the act of falling. Finally, the product assumes its angle of repose, as indicated at 152, while the bar starts towards the left on its return stroke to the initial position and displaces the material in front of it, breaking through the angle of repose at 152a, and repeating, at the left, the spilling of the product similarly to that at 151b. The back and forth travel of the bar 65 continues indefinitely, piling up the product, as at 71, on a floor 72. If desired, the product may fall onto, for example, a belt conveyor (not shown).

The differential discharge of material from the calcining chamber can now be explained in its entirety. In Fig. 5, for example, the dogs 68 are individually adjusted in harmony with any differential kiln discharge desired. If a dog is lowered until the apex of the opening 68 rests on a bar 65, then the full reciprocative strokes of the frame 60 are exerted upon the bar. If, on the contrary, the dog is raised until the lower faces of the jaws are even with the bar, then no part of the stroke is exerted upon the bar. Therefore, any dog can be adjusted to exert at either end

thereof, any fractional part of the stroke between zero and maximum.

Examples of differential movements of a bar 65 on a plate 64 are shown in Fig. 7 where the full lines 65 show the middle position of the bar relative to the plate, and the dotted lines 65b and 65c show alternate positions of the bar. In the instance of 65b, the bar has no motion at the left end, but the maximum stroke at the right end. In the instance of 65c, the bar has a small movement at the right, and only a part of the full stroke at the left.

The adjustable control dogs 68 represent merely one convenient form of control device which may be associated with the reciprocatory frame 60 for differentially controlling the movements of the respective displacement bars 65. Other devices for varying the relative strokes of the respective displacement bars and of the respective opposite ends of a single displacement bar may be employed. For instance, as illustrated in Fig. 10, pairs of adjustable limit-stop elements 97 may be threaded through spaced partitions 98 of relatively widely slotted reciprocatory longitudinal frame members 60a', so that the ends of the displacement bars 65 are disposed therebetween. Screwing of the limit-stop elements 97 of each pair varies the effective spacing therebetween, making it either greater or less, or offsetting it in one or the other direction—considered longitudinally of a frame member 60a'—from the lengthwise center of the stop plate 64 with which it is associated.

Thus, it is seen that a principle involved in the above type of variable discharge mechanism is the provision for limiting the stroke of an end of a displacement bar, as desired, within a range afforded by a predetermined maximum stroke, the limiting being accomplished by control elements which may be independently set to various limiting positions within said range.

It is to be noted that the thickness of the displacement bars should be a little less than the width of the slots 73, Fig. 5, in the reciprocatory frame members 60a and the slots in the stationary frame members 67, so they can be easily withdrawn or replaced while the frame 60 is in motion.

For reciprocating the frame 60, a connecting rod 78, which extends to a crankshaft 75, Figs. 1, 5 and 6, is provided. Obviously, the reciprocations are very slow, so that a considerable speed reduction is required between crankshaft 75 and an electric motor 76, Fig. 6, by which it is advantageously driven. Also, it is desirable to have means for changing the speed of the crankshaft between certain limits. To accomplish this two-fold purpose, a variable speed mechanism 74 of standard manufacture, such as a "Reeves," may be directly connected with the motor, the "Reeves" being in turn, belted to a compound worm-gear speed reducer 74-1, which delivers power by belt to the crankshaft 75.

An especially high degree of control can be exercised over the differential discharge of material, by utilizing displacement bars that have variously configurated longitudinal profiles, a very few of which are exemplified in Figs. 8 to 8D. In Fig. 8, the bar 140 effects a minimum spilling of material at the center, which gradually increases to a maximum at both ends. In Fig. 8A, exactly the reverse is true of the bar 141, which is shown in Fig. 9 discharging material. Such discharge should be compared with that of the corresponding portion of uniformly con-

7
figurated bar 65 in Fig. 2. In Fig. 8B, the bar 142 effects a maximum spilling of the material at one end thereof, which is gradually reduced to a minimum spilling at the other end. In Fig. 8C, the bar 143 is divided into a plurality of forms which produce maximum spilling at the high points 143a and minimum at the low points 143b. In Fig. 8D, the bar 144 is divided into three wedge-shaped sections 144a, 144b and 144c of varying lengths. Here the spilling at successive points along the bar is differentiated quite closely in proportion to the height of any particular point above the base of the bar. Obviously, the variation in the shaping of the profile of a bar is infinite, and is limited only by practical considerations of simplicity and economy.

It is to be noted that the slots in the longitudinal members 60a of the movable frame 60, as well as the slots in the longitudinal members 67 of the stationary framework in Figs. 1, 4 and 5, should be of suitable size in any given instance to accommodate the variously shaped portions of a given one of the bars 140 to 144.

Considering now the operation of the variable discharge mechanism as applied generally, if the cross-section of a body of material passing through a material treatment or processing chamber is divided into small areas, and, if, in all these small areas, even an approximate uniformity of burning or calcining can be maintained, then it follows that the summation of all the small areas, that is to say, the entire area of the aforesaid cross-section, must show substantial uniformity of calcination of the material throughout.

The chart of Fig. 12 serves as clarification. There, the outline ABCD represents the transverse or horizontal area of a material treatment or processing chamber, which, for convenience and for example, may be divided into an arbitrary number of sub-areas, such as a, b, c, d, e, and f. Each of these sub-areas may again be divided into fractional parts a1, a2 and so on, down to f4 inclusive. Each of the fractional sub-areas represents, graphically, a space in which a controlled average differential calcination may take place. The exact nature of the differential discharge is determined from time to time in accordance with the varying conditions within the chamber, as well as in accordance with the varying characteristics of any material being operated upon.

The utility of the differential or variable discharge mechanism can be very well appreciated by considering the apparatus of Fig. 1, wherein the displacement bars 65 are all of uniform rectangular profile. Here the calcining chamber or kiln 110 is fired from a combustion chamber disposed at one side thereof, as afore-explained. Consequently, the kiln wall 112 on that side is maintained hot, whereas the opposite kiln wall and the end walls 113 and 114 have radiating surfaces, so that the material adjacent thereto remains cooler than the material in other portions of the kiln. Also, the two columns a' and f', Fig. 10, immediately adjacent the end walls, are narrower than the columns b' to e' in the central portion.

In order to maintain uniform calcination in view of the conditions just described, the discharge mechanism for the different columns a' to f' are normally set as follows: all adjusting elements or dogs 68, Fig. 5, on the side opposite the combustion chamber are raised in order to

slow down, progressively across the kiln, from the hot wall on the combustion side to the cooler wall on the opposite side, the downward flow of material through the kiln. The actual slowing down is made sufficient to balance the flow of material in accordance with the heat available progressively across the kiln. As an additional adjustment, the pair of dogs 68 adjacent each end of the kiln, are raised to further slow down the flow of material in each of the corresponding end wall columns a' and f'. This additional slowing down is made sufficient to compensate for the heat radiated through the end walls, due consideration being given the fact that the respective end wall columns a' and f' are narrower than the respective central columns b', c', d' and e'.

In actual practice, where the finished product resulting from the differential discharge is allowed to pile up underneath the kiln, the contour of the pile from end to end and from side to side gives a clue or index to the kiln's performance. The pile 71 in Figs. 1 and 3, is shown in the process of building up in accordance with the performance above described. As shown, the peak 711 is the combined result of one-half of the discharge from column b', Fig. 11, plus one-half the discharge from column c'; the peak 712, one-half column c' plus one-half column d'; the peak 713, one-half column d' plus one-half column e'; the peak 714, one-half column b' plus one-half column a'; peak 715, one-half column e' plus one-half column f'; peak 716, simply one-half column a'; and peak 717, simply one-half column f'.

In Fig. 3, each of the peaks 711, 712 and 713 shows as a corresponding ridge which slopes from the high point on the combustion chamber side, back towards the opposite wall; likewise, the peaks 714 and 716 show as respective corresponding sloping ridges, all the said ridges in this figure bearing reference numerals similar to those used for the peaks in Fig. 1. As the pile 71 continues to build up, the peaks are gradually rounded out so the pile assumes a contour somewhat resembling the curved line 710, Fig. 1.

In deciding just how the discharge is to be differentially regulated during the course of any given operation, samples of the discharged material may be taken from time to time throughout the area of discharge, and the variable discharge mechanism adjusted to rectify any tendency toward over-burning or under-burning wherever the same may occur throughout the stream of material.

In Figs. 13, 14 and 15 is illustrated a variation of the above-described variable discharge mechanism. Here the stop plates themselves are the movable members which are reciprocated from side to side transversely of their lengths, while the material displacement function of the previously described displacement bars 65 is carried out by stationary displacement members extending lengthwise of and depending substantially centrally from the respective discharge spouts.

As illustrated, each stop plate 300 is positioned directly below a discharge spout 301, which corresponds to a discharge spout 31 of the preceding figures. The several stop plates extend through oppositely disposed stationary, longitudinally slotted, longitudinal frame members 302, which correspond to the slotted longitudinal members 67 of the stationary framework previously described with respect to Fig. 4 and, at their respective opposite ends, rest upon and are sup-

ported by the lower runs of such slotted longitudinal frame members 302, sliding thereupon during their limited sidewise reciprocations.

Reciprocation of the stop plates 300 is achieved in the same way as previously described for the displacement bars 65 of Figs. 1, 3 and 4, each stop plate being provided with opposite end extensions 303 which are received by respective adjustable dogs 68 or the like mounted on a longitudinal reciprocable frame, all as illustrated and described in detail with respect to the prior embodiment.

The material resting on the several stop plates 300, see Fig. 13, is displaced, i. e., pushed off or spilled, during the sidewise movements of such plates, by means of stationary displacement members 304. Such members are here advantageously secured to the respective spouts 301 with which they are associated, being preferably disposed along the longitudinal central axes of such spouts and depending therefrom to just short of contact with the material-receiving surfaces of the respective stop plates 300. In instances of other types of discharge openings, it might be found desirable to secure such members 304 to the stationary framework of the discharge mechanism, as, for instance, to the stationary longitudinal members 302, by means of end extensions (not shown) of the displacement members 304, thereby making the discharge mechanism complete in itself, as in Figs. 4 and 5. Although the displacement members 304 are shown as solid, curtain partitions, thereby effecting greater displacement per stroke than the bars 65, it is obvious that the respective depths thereof may be altered or "profiled" as desired; either the ends of a displacement member 304, which is of bar formation, serving as hangers securing it to its corresponding spout, or the profiling being carried out along its lower edge.

From the nature of the foregoing it is seen that, broadly speaking, pursuant to the invention material is displaced or spilled as desired, from a material-receiving surface, by reason of relative movement between that material-receiving surface and material displacement means. It is immaterial, in the larger view, whether the displacement means moves relative to the material-receiving surface or vice versa.

In Figs. 16, 17 and 18 is shown another embodiment of variable or differential discharge mechanism pursuant to the invention, in which hollow drums 100 made, for example, of sheet metal, and rotatably mounted in aligned groups or sets on shafts 101, provide arcuate material-receiving surface in place of the stop plates of the prior embodiments. They are placed directly underneath discharge spouts similar in construction to the discharge spouts 301 of Figs. 13 and 14, so as to leave a limited space 102 between the spout and the upper circumferential area of the drums 100. The material displacement members 304 depend to just short of touching the arcuate material-receiving surfaces of drums 100. The lower portions of the drums are cut out in the form of sectors 104, providing inverted V-shaped jaws, and projecting into the sector spaces or jaws are standards 105 which are adjustably mounted on cross-bars 106 of a reciprocable frame 107 mounted on rollers 108, this frame being connected by means of a rod 109 to a drive mechanism similar to the one indicated at 73 to 78 in Figs. 5 and 6, but not shown in Fig. 16.

In operation, supposing the frame 107 to be reciprocated, the standards 105 are adjusted to

various heights, as indicated, for example, in Fig. 17, so that the same reciprocative stroke of the frame will rotate the drums 100 through varying fractional parts of a single rotation, thereby causing the withdrawal from the discharge spouts 301 of correspondingly varying amounts of material. The adjustment of the standards 105 is effected by means of bolts 132 which extend through slots 134, Fig. 18, to secure the standards in the notches cut in the respective cross-bars 106.

In Fig. 16, four drums are shown on each shaft 101, each drum being rotatable independently and having its individual standard set at such a height as to cause the corresponding drum to spill a certain differential quantity of material in accordance with the particular setting of the standard.

Assuming that the stroke of the frame 107,

20 Fig. 17, is at the moment towards the right, then the drum 100a is being rotated counterclockwise, at the moment, meanwhile spilling material at 130, because the top of its standard 105 is in contact with the sector face 131, and will so continue, until, at the end of the stroke, the standard is in the dotted position 105a. At that time, the sector face 136 will have moved to the position 136a. On the return stroke, the standard idles until it contacts the sector face at 136a and 25 commences moving the drum clockwise, thereby gradually stopping the flow of material at 130 and starting the flow on the opposite side of the drum. This rocking back and forth of the drum, with its spilling of material first on one side and 30 then on the other, continues indefinitely. During the same time that the drum 100a is rocked as just described, the adjacent drum 100b stands still until its standard 105, in its movement towards the right, contacts the sector face 138, after 35 which, in moving to the dotted position 105c, the standard will have moved the drum 100b counterclockwise to the point where the sector faces 138 and 139 will have assumed the dotted positions 138a and 139a, respectively. This limited 40 counterclockwise movement of the drum 100b will have spilled material (not indicated) at the left of the drum, but much less in quantity than that spilled by the first drum at 130. Thus it is obvious that as any standard 105 is lowered, its 45 corresponding drum, through the increased idleness, spills less and less material, thereby making it possible, as in the case of the discharge mechanism of Figs. 4 and 5, and the discharge mechanism of Figs. 13, 14 and 15, to closely regulate 50 the performance of a material-processing chamber by means of a differential discharge of its finished product.

The chart of Fig. 12 gives an idea of how closely the discharge of treated or processed material 60 can be regulated by the novel variable discharge mechanism of the invention. The areas of the rectangles designated a, b, c, d, e and f, each comprising four sub-areas, represent those fractional parts of the total treatment or processing zone 65 controlled by the respective sets of movable means and displacement means of any of the above-described embodiments. The discharge within the area represented by any one of the rectangles is controlled wholly independently of 70 the discharge within the area represented by any of the other rectangles. In the case of a displacement bar 65 or of a movable plate 300, the dog at one end of the bar may be set higher than the dog at the opposite end, with the result that 75 the sidewise oscillations of the bar or plate will

have a lesser amplitude at the said one end portion thereof than at the said opposite end, the amplitude gradually increasing along the length of the bar or plate from the said one end to the said opposite end. Accordingly, there is a differential discharge, fractionally, from end-to-end of each one of the rectangular areas *a*, *b*, *c*, *d*, *e* and *f*. This differential discharge is arbitrarily represented by the fractional sub-area *1*, *2*, *3* and *4* of each rectangle.

By varying the profile of a displacement bar 35 or of a displacement member 304 along its length, it is possible to obtain substantially any desired rate of discharge within the sub-areas *1*, *2*, *3* and *4* of any rectangle.

In the case of a set of drums 100, the several standards 105 may be individually positioned to govern the discharge differentially, in accordance with the sub-areas *1*, *2*, *3* and *4* of any rectangle.

Whereas specific forms of the apparatus of the invention are here illustrated and described, it should be understood that various changes may be made in such specific forms and various other forms may be produced by those skilled in the art to which this invention appertains, without departing from the spirit and generic purview of the invention as defined in the following claims.

Having fully described my invention, what I claim is:

1. In combination, walls defining an elongate gravity discharge opening; stop means having a material-receiving surface spaced substantially directly below said discharge opening and adapted to normally stop gravity flow of material from said discharge opening; an elongate displacement bar mounted between said discharge opening and said stop means for controlled movement transversely of said discharge opening and of said stop means, the transverse movement of said bar being adapted to displace material resting on said stop means and to thereby discharge a corresponding quantity of material from said receiving surface of said stop means; independently settable control elements arranged to engage opposite ends of said bar for imparting differential movement thereto so as to discharge material from said stop means variably along the length of said bar; and drive means for said control elements.

2. In combination, walls defining a plurality of gravity discharge openings arranged in series; a correspondingly arranged series of stop plates respectively spaced directly below the said discharge openings, and adapted to normally stop gravity flow of material from said discharge openings; a correspondingly arranged series of displacement bars respectively mounted between corresponding stop plates and discharge openings of the series of same for controlled, individual movement transversely of said stop plates and of said discharge openings; movable members extending transversely of said series of bars adjacent opposite ends of said bars, and arranged for reciprocation in the direction of their lengths; a plurality of independently settable control elements operatively associated with said movable members and arranged to engage opposite ends of respective bars for moving the respective opposite ends of each bar by reason of the reciprocation of said movable members; and means for reciprocating said movable members in the direction of their lengths.

3. A gang, flow-controlling, discharge device, comprising a chamber; a plurality of spouts placed relatively close together in the bottom of

said chamber, and forming a series of elongated, substantially parallel, gravity discharge openings leading from said chamber; a stationary plate mounted under each opening, substantially directly below the same and spaced therefrom; a displacement member mounted between each plate and discharge opening; means to impart a transverse reciprocating travel to all of the displacement members of the said series; means to vary the speed of travel of said means, and to thereby vary the total discharge per unit time from said chamber; and a plurality of independently settable control means to independently vary the distance of travel of opposite ends of each of said members, thereby varying at will the flow through and discharge from the chamber, differentially, along both the length and the breadth of the transverse discharge area of said chamber.

20 4. In combination, a plurality of gravity discharge spouts; a corresponding plurality of stop plates respectively spaced substantially directly below the said discharge spouts and arranged to normally stop discharge flow of material therefrom; stationary frame means substantially bounding said plurality of stop plates; movable frame means substantially commensurate with the area comprehended by said plurality of stop plates, and arranged for reciprocatory movement 25 transversely of said discharge spouts; pairs of dog devices corresponding in number to the number of said stop plates, the individual dog devices of each pair being spaced apart across the width of said movable frame means and adjustably secured thereto; a plurality of displacement bars corresponding in number to the number of said stop plates and disposed thereabove, respectively, said bars being supported near opposite ends thereof by said stationary frame, and having the said opposite ends thereof arranged for engagement by said dog devices, respectively, as said movable frame means reciprocates, said dog devices being arranged to push their respectively associated bar ends respective distances, during 30 the reciprocation of said movable frame means, which vary according to the particular adjustments of the respective dog devices, thereby displacing quantities of material from said stop plates, said quantities varying along the lengths 35 of the respective bars in accordance with the relative movements of the respective opposite ends of the said bars.

5. In combination, a plurality of gravity discharge spouts; a corresponding plurality of stop plates respectively spaced substantially directly below the said discharge spouts and arranged to normally stop discharge flow of material therefrom; a plurality of displacement bars corresponding in number to the number of said stop plates and overlying said stop plates, respectively; sidewise means supporting said bars; means for moving said bars in common; and a plurality of individually adjustable control elements associated with said moving means and arranged to engage and to impart sidewise movement to the opposite ends of said bars, respectively, said adjustable control elements being individually adjustable relative to one another to vary the distance through which the respective ends of the said bars are caused to move.

6. A feeder of the class described, comprising a plurality of feed spouts forming a series of gravity discharge openings; a stationary plate spaced substantially directly below each opening; a displacement bar mounted between each plate and

13

discharge opening; movable members mounted at opposite ends of the displacement bars of the series and extending at least the full length of the said series; individually adjustable control elements associated with said movable members to impart motion to each displacement bar by reason of the movement of said movable members; and means for actuating the said movable members.

7. A feeder of the class described, comprising a plurality of feed spouts forming a series of gravity discharge openings; a stationary plate spaced substantially directly below each opening; a displacement bar mounted between each plate and discharge opening; a movable frame comprehending said series of discharge openings, vertically adjustable dogs, each dog having a vertically tapered notch therein, said dogs being secured to said movable frame adjacent opposite ends of the displacement bars so that their notches respectively engage the said opposite ends of the displacement bars; and drive means for horizontally reciprocating said movable frame and said dogs transversely of the length of said displacement bars for imparting relative movement to the said opposite ends of the displacement bars.

8. A device as set out in claim 7, wherein the drive means is adjustable to change the speed of reciprocation of the dogs.

9. A device of the class described, comprising a plurality of feed spouts forming a series of gravity discharge openings; a stationary plate spaced substantially directly below each opening; a displacement bar mounted between each plate and discharge opening; substantially horizontal stationary guides for maintaining the displacement bars at a fixed horizontal level; movable members mounted at opposite ends of the displacement bars of the series, extending at least the full length of said series, and having a fixed reciprocating travel; means for actuating said movable members; and a plurality of independently adjustable control elements secured to said movable members and arranged to independently engage opposite ends of the respective displacement bars to impart any desired amount of the fixed travel of the movable members independently to each end of the said displacement bars.

10. A feeder according to claim 6, wherein the shape of a displacement bar varies longitudinally thereof.

11. A device according to claim 9, wherein a displacement bar varies in shape longitudinally thereof.

12. Variable discharge mechanism, comprising in combination, a plurality of mutually spaced, elongate stop means having material-receiving surfaces adapted to be disposed substantially directly below the open bottom of a chamber; a corresponding plurality of material displacement means positioned between said material-receiving surfaces and said open bottom; and drive means arranged for effecting relative movement between said stop means and said displacement means so as to cause material to spill off said material-receiving surfaces, said drive means including a plurality of selectively positionable motion-transmitting elements, one of which elements is positioned at each of the opposite ends of the respective stop means and displacement means, for independently imparting said relative movement at said opposite ends and for determining the relative quantities of said material spilled at different

14

locations along the lengths of the respective material-receiving surfaces.

13. A device of the class described, comprising a plurality of spouts forming a series of gravity discharge openings; a corresponding plurality of partitions fastened to and depending from the respective discharge openings; a corresponding plurality of movable stop means disposed below the respective discharge openings for respective movement transversely of said partitions; movable longitudinal members mounted at opposite ends of the respective stop means of said series, extending at least the full length of said series, and having a fixed reciprocating travel longitudinally thereof; a plurality of independently adjustable drive elements arranged to impart any desired amount of the fixed travel of the said movable longitudinal members, independently, to opposite ends of each stop means; and means for actuating said movable members.

14. A device of the class described, comprising a plurality of spouts forming a series of gravity discharge openings; a corresponding plurality of stop means mounted for lateral movement substantially directly below the respective discharge openings and spaced therefrom; and means to impart independently to opposite ends of each stop means, transverse reciprocatory travel, said means comprising a plurality of independently adjustable drive elements arranged at opposite ends of said stop means, a single one of said drive elements at each of said opposite ends of said stop means.

15. Variable discharge mechanism, comprising in combination, stop means, which includes a set of independent stop members disposed side by side and mounted for separate and independent rocking movement on a common axis, said stop members having respective material-receiving surfaces aligned side by side along said common axis and adapted to be disposed substantially directly below a discharge opening; material displacement means positioned between said material-receiving surface and said discharge opening; and drive means for moving said stop means relative to said material displacement means so as to cause material to spill off said respective material-receiving surfaces, said drive means including selectively positionable drive elements arranged for respective cooperation with the stop members of said set in determining the respective extents of rocking movements of said stop members relative to one another and the relative quantities of said material spilled by the respective material-receiving surfaces of said stop members.

16. Variable discharge mechanism, comprising in combination, stop means, which includes a set of independent stop members disposed side by side and mounted for separate and independent rocking movement on a common axis, said stop members having respective material-receiving surfaces aligned side by side along said common axis and adapted to be disposed substantially directly below a discharge opening, said stop members having, further, respective inverted V-shaped jaws disposed below said material-receiving surfaces and arranged for rocking movement therewith; material displacement means positioned between said material-receiving surface and said discharge opening; and drive means for moving said stop means relative to said material displacement means so as to cause material to spill off said respective material-receiving surfaces, said drive means including selec-

15

atively positionable standards extending, respectively, into said jaws for imparting the motion of said drive means differentially to the respective stop members in accordance with the respective relative positions of said standards, thereby determining the respective extents of rocking movements of said stop members relative to one another and the relative quantities of said material spilled by the respective material-receiving surfaces of said stop members.

17. A device of the class described, comprising a plurality of spouts forming a series of gravity discharge openings; a corresponding plurality of movable stop means disposed below the respective discharge openings for respective movement transversely of said spouts; movable carrier means extending at least the full length of said series and arranged to travel longitudinally thereof; a plurality of sets of independently adjustable drive elements carried by said carrier means, each of said sets being arranged to impart any desired amount of the travel of the said

5

10

15

20

movable means, independently, to mutually different parts of a single stop means; and means for moving said carrier means.

THOMAS R. ELLERBECK.
